MAGNETIC ROLL CONVEYER

Samuel N. Findlay and Loren A. Hayes, Elyria,
Ohio, assignors to National Tube Company, a
corporation of New Jersey

Application September 12, 1946, Serial No. 696,596

5 Claims. (Cl. 198—41)

1

This invention relates to an improved magnetic roll conveyor for use in conveying magnetizable articles. The roll conveyor of the present invention displays its greatest advantages when employed for conveying elongated articles in the direction of their axes.

The invention has among its objects the provision of an improved magnetic roll conveyor characterized by its simplicity of construction and the economy and ease with which it is maintained.

A further object of the invention lies in the provision of a magnetic roll conveyor having small flux leakage and in which the flux is distributed in the article being conveyed in substantially the optimum manner.

A still further object of the invention is the provision of an improved magnetic roll having greatly improved wearing qualities.

These and further objects of the invention will be more fully apparent in the following description.

It is often necessary to convey magnetizable articles, for example, long lengths of iron or steel pipe or rods, without employing the usual pinch rolls, gripping means, or other devices frictionally engaging the articles to overcome their inertia and move them in the direction of their axes. Threaded pipe, for instance, has been found to be damaged by such gripping and forwarding means since their engagement deforms the threads on the pipe. For the purpose of conveying such articles, magnetic roll conveyors have been employed, such conveyors depending upon the attraction of a magnetic field to hold the articles in tight frictional engagement with the converging rolls upon which they rest.

The most widely used magnetic roll conveyor for such purpose has been one in which magnetic coils are incorporated within the roll itself. The coils being powered through lead wires from rotating slip rings attached to the roll shaft, such slip rings cooperating with stationary brushes. Such devices have been costly, however, because of the necessity of such slip rings and brushes and the maintenance costs of such devices have been high. Furthermore, in such designs it is impossible to produce the optimum flux distribution in the article being conveyed by coils positioned within the roll, and the magnetic leakage is excessive.

The magnetic roll conveyor of the present invention provides a magnetic roll upon which the article to be conveyed rests, such roll being positioned between two stationary pole pieces located longitudinally of the article, such pole pieces being normally spaced from the article. The magnetic circuit is such that the roll forms a magnetic pole with one polarity, and the two stationary pole pieces between which it is positioned

2

are of the same polarity but opposite from that of the roll.

The invention will be more readily understood by reference to the following drawings, in which:

5 Figure 1 is a view in side elevation of a preferred embodiment of the magnetic roll conveyor assembly, portions of the side guide and roll supporting bearing being omitted; the view in Figure 1 is taken along the line I—I of Figure 2;

10 Figure 2 is a view in vertical cross-section through the axis of the magnetic conveyor roll, such view being taken along the line II—II of Figure 1;

Figure 3 is a view in plan of the apparatus shown in Figures 1 and 2;

15 Figure 4 is a view in vertical cross-section through the axis of the magnetic conveyor roll of a modification of the apparatus for conveying flat articles; and

20 Figure 5 is a view in plan of the modified apparatus shown in Figure 4.

The embodiment of the apparatus shown in Figures 1, 2, and 3 is designed to convey pipes made of magnetizable material, such as pipes of iron and steel. Such device may be used to advantage in the conveying of pipes to hot dip coating machines although it is to be understood that its use is not to be so limited. In the drawing there is shown one magnetic roll assembly with idle rolls on either side, but it is to be understood that any number of magnetic roll assemblies may be employed, depending upon the weight of the article to be conveyed and the length of the path which it must traverse. The magnetic roll conveyor assembly is supported on two parallel longitudinally extending structural members 2 and 4 attached to a base (not shown) and suitably cross braced by members (not shown) below the conveyor roll assembly. A motor support 6 extends parallel to supports 2 and 4 and may, if a plurality of magnetic conveyor rolls are employed, extend continuously for the support of the plurality of motors.

45 The magnetic conveyor roll, designated generally by the reference character 8, is supported on and keyed to the driving shaft 10 which extends through and is supported in bearings in the support 2, and through the side guide 13, which is secured to support 2, and at its opposite end through the side guide 15 and the roll supporting plate 12, in which it is also supported in bearings (not shown). Plate 12 is secured to support 4 by a plurality of studs 14, of which one is shown in Figure 2. The roll supporting and driving shaft 10 is driven by electric motor 16, the shaft 18 of which is connected to the driving shaft 10 by means of a flexible coupling 20.

55 The magnetic conveyor roll 8 consists of a main body portion 22 having an end flange 24 thereon and a part 26 of reduced diameter. The roll body

60

is provided with the cap 28, the inner end of which fits over the outer end of part 26 of body portion 22. Both parts 22 and 28 are made of non-magnetic material such as brass. As shown, the cap is secured to part 22 by means of countersunk studs 30. Secured upon the reduced diameter portion 26 and clamped between the flange 24 and the inner end of cap 28 is the soft steel serrated or grooved ring 32 which forms the central magnetic pole of the device magnetic roll assembly. Roll 8 is secured to shaft 16 by means of the key 33, the set screw 34 in body portion 22 preventing the roll from moving longitudinally with respect to the shaft.

5

In order to function efficiently as a magnetic pole the ring 32 is, as stated, of soft steel. Such steel, however, would wear excessively through contact with the articles conveyed if it were not protected. In the present device such protection takes the form of hard metal inserts 38 positioned in equally spaced longitudinal grooves 36 in the outer surface of the ring. Inserts 38, which may be of a hard metal such as the cobalt base alloy marketed under the trade-mark "Stellite," thus prevent the pipe 40 being conveyed from wearing the soft steel of the ring where such steel extends to the outer surface of the ring between inserts 38. The outer surface of ring 32 is made generally to conform to a portion of the cross-section of the article being conveyed. For rounds the outer surface of the ring is made with the dished shape, in an axial plane, shown in Figure 2.

ments of the magnetic roll conveyor of the present invention it is to be understood that variations are possible and that our invention is defined by the following claims.

We claim:

1. A device for conveying elongated magnetizable articles comprising a support furnishing bearings axially aligned in a substantially horizontal direction, a magnetizable conveyor roll rotatably mounted in said bearings and adapted to convey articles in a path tangential to the upper edge of its circumference, means spaced from said roll for additionally supporting the articles, drive means for rotating said roll, fixed magnetic means carried by said support and transmitting magnetic flux to said roll and thereby making the upper edge of the circumference a magnetic pole, and magnetizable means carried by said magnetic means furnishing a pole of polarity opposite that of the upper edge of the roll circumference proximate to the article carrying path and spaced from the upper edge of the roll circumference.

2. A device for conveying elongated magnetizable articles comprising a fixed support furnishing bearings axially aligned in a substantially horizontal direction, a magnetizable conveyor roll rotatably mounted in said bearings and adapted to convey articles in a path tangential to the upper edge of its circumference, means spaced from said roll for additionally supporting the articles, drive means for rotating said roll, a pair of magnets carried by said support at opposite sides of the axis of rotation of said roll, said magnets having inwardly directed poles of like polarity facing each other, magnetizable means between said inwardly directed poles and said roll transmitting magnetic flux to said roll and thereby making the upper edge of the circumference a pole of the same polarity as said inwardly directed poles, said magnets having outwardly directed poles of polarity opposite that of said inwardly directed poles, and magnetizable means connected to said magnets at said outwardly directed poles and extending to the proximity of the article carrying path and furnishing poles of polarity opposite that of the upper edge of the roll circumference.

3. A device for conveying elongated magnetizable articles comprising a fixed support furnishing bearings axially aligned in a substantially horizontal direction, a magnetizable conveyor roll rotatably mounted in said bearings and adapted to convey articles in a path tangential to the upper edge of its circumference, means spaced from said roll for additionally supporting the articles, drive means for rotating said roll, a pair of magnets carried by said support beneath said roll and at opposite sides of the axis of rotation thereof, said magnets having inwardly directed poles of like polarity facing each other, a magnetizable insert between said inwardly directed poles and said roll and having a concave upper face complementary to said roll, said insert transmitting magnetic flux to said roll and thereby making the upper edge of the circumference a pole of the same polarity as said inwardly directed poles, said magnet having outwardly directed poles of polarity opposite that of said inwardly directed poles, and magnetizable bars connected to said magnets at said outwardly directed poles and extending to the proximity of the article carrying path at opposite sides of said roll and furnishing poles of

polarity opposite that of the upper edge of the roll circumference.

4. A device for conveying elongated magnetizable articles comprising a fixed support furnishing bearings axially aligned in a substantially horizontal direction, a magnetizable conveyor roll rotatably mounted in said bearings and adapted to convey articles in a path tangential to the upper edge of its circumference, rotatable means at opposite sides of said roll for additionally supporting the articles, drive means for rotating said roll, a continuous magnetizable core carried by said support beneath said roll and transverse to the axis of rotation, a pair of solenoids on said core at opposite sides of the axis of rotation, said solenoids having windings adapted to furnish inwardly directed poles of like polarity facing each other, a magnetizable insert received on said core between said solenoids and having a concave upper face complementary to said roll, said insert transmitting magnetic flux to said roll and thereby making the upper edge of the circumference a pole of the same polarity as said inwardly directed poles, said solenoids furnishing outwardly directed poles on said core of polarity opposite that of said inwardly directed poles, and bars carried by the ends of said core outside said solenoids and extending to the proximity of the article carrying path at opposite sides of said roll and furnishing poles of polarity opposite that of the upper edge of the roll circumference.

5. A device for conveying elongated magnetizable articles comprising a fixed support furnishing bearings axially aligned in a substantially horizontal direction, a conveyor roll rotatably mounted in said bearings and having an annular soft steel segment around its circumference and harder wear resistant inserts in said segment, said roll being adapted to convey articles in a path tangential to the upper edge of its circumference, rotatable means spaced from said roll at opposite sides thereof for additionally supporting the articles, drive means for rotating said roll, a pair of electromagnets carried by said support at opposite sides of the axis of rotation of said roll, said magnets having inwardly directed poles of like polarity facing each other, magnetizable means between said inwardly directed poles and said roll transmitting magnetic flux to said annular segment and thereby making the upper edge of the circumference a pole of the same polarity as said inwardly directed poles, said electromagnets having outwardly directed poles of polarity opposite that of said inwardly directed poles, and magnetizable means connected to said electromagnets at said outwardly directed poles and extending to the proximity of the article carrying path and furnishing poles of polarity opposite that of the upper edge of the roll circumference.

Certificate of Correction

February 14, 1950

Patent No. 2,497,162

SAMUEL N. FINDLAY ET AL.

It is hereby certified that error appears in the printed specification of the above numbered patent requiring correction as follows:

Column 1, line 37, for the word "converging" read *conveying*;
and that the said Letters Patent should be read with this correction therein that the
same may conform to the record of the case in the Patent Office.

Signed and sealed this 13th day of June, A. D. 1950.

[SEAL]

THOMAS F. MURPHY,
Assistant Commissioner of Patents.
